UNITED STATES PATENT OFFICE.

ROBERT E. SMITH, OF ST. LOUIS, MISSOURI.

RAILWAY-BED CONSTRUCTION.

SPECIFICATION forming part of Letters Patent No. 762,207, dated June 7, 1904.

Application filed December 24, 1903. Serial No. 186,472. (No model.)

To all whom it may concern:

Be it known that I, ROBERT E. SMITH, a citizen of the United States, residing at St. Louis, State of Missouri, have invented certain new and useful Improvements in Railway - Bed Construction, of which the following is a specification containing a full, clear, and exact description, reference being had to the accompanying drawings, forming a part hereof.

10 My invention relates to railway-beds, my object being to reduce the amount of wood required for ties in railway - bed construction and to give the bed increased strength and durability.

15 My improved railway - bed construction comprises the combination, with a suitable grade, of two parallel rows of ties laid end to end, dowel-pins connecting the ties, anchors embedded in the grade below and between the

20 rails, tie-rods connecting the rails, anchor-rods connecting the ends of the tie-rods inside of the rails to the anchors, and anchor-plates connected to the tie-rods outside of the rails and embedded in the grade.

25 Figure 1 is a cross-section of a railway-bed construction embodying the principles of my invention. Fig. 2 is a top plan, parts being shown in section and other parts being broken away. Fig. 3 is a sectional view showing how 30 the ties are connected by dowel-pins.

Referring to the drawings in detail, the wooden ties 4 are laid end to end in two parallel rows upon the grade 5, the ends of said ties being connected by the dowel-pins 6. The 35 rails 7 are mounted upon the ties 4 and secured to said ties by the spikes 8. Wells are dug in the grade 5 between and below the rails. The anchors 9 are placed in said wells, and the wells are filled around the anchors, 40 with cement or concrete 10. The anchors, as shown, are sections of corrugated tubes, this being a very favorable form of anchor, because it will sit firmly in the bed of cement; but other forms may be used. Openings 9^a 45 are formed in the wall of the anchor 9, and cement passes through said openings to fill the tube. The tie-rods 11 have their ends inserted through the rails 7, and the anchor-rods 12 and 13 extend downwardly and in-

wardly from the ends of the tie-rods inside of 50 the rails and have hooks 14 to engage in the anchor 9, said anchor-rods being connected to the anchors, preferably before the cement is placed, and after the cement is placed the wells are filled and the grade finished between 55 the rails. The anchor-plates 15 are placed in position outside of the rails with the ends of the tie-rods 11 extending through said anchor-plates, said anchor-plates extending downwardly and outwardly outside of the rails, 60 and when the grade is finished said plates are embedded in the grade. The nuts 16 are screw-threaded upon the extreme outer ends of the tie-rods and hold the parts firmly together. 65

A great saving in ties is effected by laying the ties end to end. The system of anchorage effectually prevents the ties and rails from moving laterally upon the grade.

I claim—

1. A railway-bed construction, comprising the combination with a suitable grade, of two parallel rows of ties laid end to end; dowel-pins connecting the ties; anchors embedded in the grade below and between the rails; tie-rods connecting the rails; anchor-rods connecting the ends of the tie-rods inside of the rails to the anchors; anchor-plates connected to the tie-rods outside of the rails and embedded in the grade, substantially as specified. 80

2. In a railway-bed construction, a suitable grade, ties mounted end to end upon the grade, rails mounted upon the ties, anchors embedded in the grade below and between the rails, and anchor-rods extending upwardly and outwardly from the anchors to the rails, thereby connecting the rails to the grade and thereby connecting the rails together through the anchors, substantially as specified. 85

3. In a railway-bed construction, a suitable grade; ties laid end to end upon the grade; rails upon the ties; tie-rods connecting the rails; and means of anchoring the rails to the grade, substantially as specified.

4. In a railway-bed construction, a suitable grade; ties laid end to end upon the grade; rails upon the ties; anchors embedded in the grade; tie-rods connecting the rails; and an-

chor-rods connecting the tie-rods to the anchors; substantially as specified.

5. In a railway-bed construction, the combination with a suitable grade, of ties laid end to end; rails upon the ties; anchors embedded in the grade below and between the rails; anchor-rods connecting the tie-rods to the anchors; and anchor-plates connected to the rails and extending downwardly and outwardly

outside of the rails and embedded in the grade, 10 substantially as specified.

In testimony whereof I have signed my name to this specification in presence of two subscribing witnesses.

ROBERT E. SMITH.
